Patented Apr. 1, 1975

234,703

BIRD FEEDER

James C. Fry, Wooster, Ohio, assignor to
Rubbermaid Incorporated, Wooster, Ohio

Filed May 18, 1973, Ser. No. 361,799

Term of patent 14 years

Int. Cl. D30—03

U.S. Cl. D30—13

FIG. 1

FIG. 4

FIG. 2

FIG. 3

FIG. 5

FIG. 1 is a top plan view of a bird feeder embodying my new design.

FIG. 2 is a front elevational view;

FIG. 3 is a side elevational view;

FIG. 4 is a top plan view thereof with the roof removed.

FIG. 5 is a cross-sectional view along line 5—5 of FIG. 1.

The roofing pattern shown in FIGS. 1 and 2 is continuous within the boundary thereof.

I claim:

The ornamental design for a bird feeder, as shown and described.
